Primary Examiner — Deanna L Pratt*Assistant Examiner* — Harold Blackwell, II(74) *Attorney, Agent, or Firm* — Arent Fox LLP(57) **CLAIM**

The ornamental design for a connector plate, as shown and described.

DESCRIPTION

FIG. 1 is a perspective view of a connector plate showing my new design;

FIG. 2 is a top view thereof;

FIG. 3 is a first side view thereof;

FIG. 4 is a second, opposing side view thereof;

FIG. 5 is a back view thereof; and,

FIG. 6 is a front view thereof.

The broken lines in the drawing are for the purpose of illustrating unclaimed portions of the connector plate and form no part of the claimed design.
